UNITED STATES PATENT OFFICE.

JOHN W. ANDERSON, OF ST. LOUIS, MISSOURI.

INSIDE BLIND.

SPECIFICATION forming part of Letters Patent No. 357,888, dated February 15, 1887.

Application filed March 14, 1885. Renewed January 11, 1887. Serial No. 224,057. (No model.)

To all whom it may concern:

Be it known that I, JOHN W. ANDERSON, a citizen of the United States, and a resident of St. Louis, in the county of St. Louis and State 5 of Missouri, have invented certain new and useful Improvements in Inside Blinds for Windows; and I do hereby declare that the following is a full, clear, and exact description of the invention, which will enable others skilled in the art to which it appertains to make and use the same, reference being had to the accompanying drawings, which form a part of this specification, and in which—

Figure 1 is a front view of my improved inside blind, showing the same applied to a window in position for operation. Fig. 2 is a side view of the same, with dotted lines showing the slats in a raised position; and Figs. 3 and 4 are perspective views, on a larger scale, of the 20 sockets or clamps used at the two ends of the slats.

The same letters refer to the same parts in all the figures.

My invention has relation to that class of window-blinds which are composed of a number of slats connected so as to have their edges overlapping each other, having cords for drawing them up to rest with their flat sides packed close upon each other, and having cords or 30 chains attached near their edges, by means of which the inclination of the slats may be regulated; and it consists in the improved construction and combination of parts of the same, as hereinafter more fully described and claimed.

35 In the drawings hereto annexed, A designates the window-frame to which my improved blind has been applied.

B designates the blind, which is composed of a series of slats, C C, the ends of which are provided with metallic clamps or sockets. (Designated, respectively, by D and D'.) Said sockets are provided with staples E E', by which they are pivoted or connected to the links F of the chains G, whereby the slats are connected so as to form the blind. When the latter is extended, the slats will overlap each other, as will be seen in Fig. 2 of the drawings.

45 The upper ends of the connecting-chains are attached within a box-like cornice or casing, H, 50 which is secured under the top of the window-frame, and which serves to receive and accommodate the blind when the latter is folded.

I is a cord passing around the blind under the bottom slat, as shown, and the ends of which pass over a pair of parallel pulleys, J 55 J, arranged in the cornice-box, respectively in front and in rear of the blind. The ends of the cord pass together through a screw-eye or guide, K, and over a pulley, L, at one end of the cornice-box, whence it depends so as to be 60 readily reached and manipulated for the purpose of raising or lowering the blind, as the case may require. The sockets D' at one end of the blind are, in addition to the staples E', provided with perforated lugs or eyes M at their 65 lower corners, whereby they are attached to a cord, N, running over a pulley, O, at one end of the cornice-box, whence it hangs down within easy reach of the operator, who, by pulling the said cord, will lift the lower free 70 edges of the slats, which are thus raised to an approximately horizontal position, so as to offer no hinderance to ventilation.

The operation of this invention will be readily understood from the foregoing description, 75 taken in connection with the drawings hereto annexed. When the depending ends of the cord I are released, the blind will be unfolded by its own weight. By pulling the said cord the blind may be partially or entirely folded, 80 and it may be thus retained by simply making the cord I fast to some suitable hook attached to the window frame or sill. By pulling the cord N the slats of the blind, or as many of them as are at the time unfolded, may be 85 raised toward a horizontal position, as shown in Fig. 2, for the purpose of ventilation. The cord N may also be made fast in any suitable manner.

It will be seen that the metallic caps at the 90 ends of the slats will serve as secure points of attachment for the connecting-chains and for the adjusting-cord, avoiding the necessity of securing cords or staples to the slats, which are preferably strips of wood, which would 95 easily split or break during use.

I am aware that slat-blinds have been made having chains connecting the slats, so as to have their edges overlapping each other, and having cords or chains connected to their free 100 edges for the purpose of adjusting the angle of inclination of the slats, and I do not wish to make any broad claims for such constructions; but

I claim—

1. In a window-blind composed of slats, the combination of the slats with metallic caps fitting upon the ends of the slats and provided with staples for the attachment of the connecting and adjusting cords or chains, as and for the purpose shown and set forth.

2. In a slat window-blind, the combination of the slats, metallic caps fitting upon one end of the slats and having staples at their ends, metallic caps fitting upon the other ends of the slats and having each a staple and an eye at

their ends, said eyes being near the front edges of the caps, chains attached to the staples and connecting the slats, and an adjusting-cord attached to the eyes, as and for the purpose shown and set forth.

In testimony that I claim the foregoing as my own I have hereunto affixed my signature in presence of two witnesses.

JOHN W. ANDERSON.
